(57) **CLAIM**

The ornamental design for a scent pad for hunting scent generator as shown and described.

DESCRIPTION

FIG. 1 is a perspective view of a first embodiment of a scent pad for hunting scent generator showing my new design.

FIG. 2 is a front elevation view thereof.

FIG. 3 is a right side elevation view thereof.

FIG. 4 is a left side elevation view thereof.

FIG. 5 is a rear elevation view thereof.

FIG. 6 is a top plan view thereof.

FIG. 7 is a bottom plan view thereof.

FIG. 8 is a perspective view of a second embodiment of a scent pad for hunting scent generator showing my new design.

FIG. 9 is a front elevation view thereof.

FIG. 10 is a right side elevation view thereof.

FIG. 11 is a left side elevation view thereof.

FIG. 12 is a rear elevation view thereof.

FIG. 13 is a top plan view thereof.

FIG. 14 is a bottom plan view thereof.

FIG. 15 is a perspective view of a third embodiment of a scent pad for hunting scent generator showing my new design.

FIG. 16 is a front elevation view thereof.

FIG. 17 is a right side elevation view thereof.

FIG. 18 is a left side elevation view thereof.

FIG. 19 is a rear elevation view thereof.

FIG. 20 is a top plan view thereof; and,

FIG. 21 is a bottom plan view thereof.

The dot dash lines in the Figures represent unclaimed boundary lines and form no part of the claimed design. The features of the scent pad for hunting scent generator depicted in dashed lines form no part of the claimed design.

1 Claim, 15 Drawing Sheets
